TELEPHONE SWITCHBOARD SYSTEM

Bernard C. Groh, Orange, N. J., assignor to the
United States of America as represented by the
Secretary of War

Application November 6, 1945, Serial No. 627,082

2 Claims. (Cl. 179—51)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention relates to telephone switchboard systems.

Presently used switchboards are characterized by the use of ringing and listening keys. Operation of these keys is time and energy consuming, and it is a prime object of the invention to provide a simplified switchboard system that will not necessitate the use of keys. It is a further object of the invention to provide such a switchboard in a form that will be simple and rapid in operation, whereby a great number of calls may be accurately and quickly handled by a switchboard operator.

These objects, and other objects and advantages of the invention, will be apparent from the following description of a preferred embodiment of the invention read in connection with the accompanying drawing, in which the figure shows schematically the electrical circuit of a switchboard, two telephone lines and the respective terminal jacks only being shown for the purpose of illustrating the system.

Referring to the drawing, the switchboard includes a first pair of jacks 10 and 12 terminating a telephone line 14, a first annunciator 16 positioned across the jack 10, a second pair of jacks 10' and 12' terminating a telephone line 14', a second annunciator 16' positioned across the jack 10', an operator's set 18 and a patch cord 20.

The jack 10 is a standard three conductor jack and comprises a tip contact 22, a ring contact 24 and a sleeve contact 26, the sleeve contact 26 being electrically connected to the ring contact 24 through a breaker point 28.

The jack 12 is a standard two conductor jack and comprises a tip contact 30 and a sleeve contact 32, the said sleeve contact 32 being electrically connected to the sleeve contact 26 of jack 10 through a conductor 34 and said tip contact being connected to the tip contact 22 of jack 10 through a conductor 35.

The annunciator 16 is a standard annunciator and includes a pivoted drop 36 responsive to a magnetic field set up by a current flowing through a coil 38. The coil 38 is connected across the jack 10, one leg of said coil being connected to

2

the tip contact 22 through a breaker point 40. Jacks 10' and 12' are identical respectively with jacks 10 and 12, each pair of jacks being the terminal equipment for a different telephone line. Similarly, the annunciator 16' is identical to the annunciator 16.

For convenience of illustration, only two lines, 14 and 14', together with their respective jacks and annunciators are shown in the drawing. It will be understood, however, that this system is designed to operate with a plurality of telephone lines terminated at the switchboard.

The operator's set 18 comprises a three conductor plug 42, a ringback key 44, a generator 46 and an operator's phone 48. The plug 42 is a standard three conductor plug and comprises a tip 50, a ring 52 and a sleeve 54. The ringback key 44 is a standard key and includes a breaker point 56 and a switch having breaker points 58 and 60, the points 56 and 58 normally being closed. The generator 46 is connected across the tip 50 and the sleeve 54 of the plug 42 through the key 44 and incorporates a normally open switch 62 having breaker points 64 and 66, which switch is automatically closed by the operation of the generator in accordance with standard commercial practice. The operator's phone 48 is connected across the tip 50 and the ring 52 of plug 42 through the breaker point 56 of the key 44. The sleeve 54 of plug 42 is connected to the ring 52 through the key 44 and the switch 62 in its open position. The power and filter elements of the operator's set 18 are of standard commercial design and are not shown.

The patch cord 20 is of the two conductor type and is terminated by a pair of standard two conductor plugs 68 and 70.

The operation of the system will now be described, with the view of illustrating the extreme simplicity thereof. Assume that a signal is generated in the line 14 by the telephone set 72. The current passing through the annunciator 16 will cause the pivoted drop 36 to operate, thereby notifying the switchboard operator that a signal has been impressed on the line 14. The operator will then connect the operator's set 18 to the line 14 by inserting the plug 42 into the jack 10.

The insertion of the plug 42 into the jack 10 will cause the tip contact 22 of jerk 10 to move downward, thus operating breaker point 40 and

thereby removing the annunciator 16 from the line, and will cause the ring contact 24 of jack 10 to move upward, thus operating the breaker point 28 and disconnecting the ring contact 24 from the sleeve contact 26.

It will thus be seen that the ring contact 24 of jack 10 will be in electrical connection with the ring 52 of plug 42 and that the tip contact 22 of the jack 10 will be in electrical connection with the tip 50 of the said plug, thereby connecting the operator's set 18 to the telephone set 72 and enabling the switchboard operator to converse with the subscriber at the telephone set 72 on line 14.

Assume that the said subscriber on line 14 desires to be connected with the subscriber on line 14'. The operator will insert the plug 68 of patch cord 20 into the jack 12 and will insert the plug 70 into the jack 10'. There will thus be established a continuous circuit between telephone set 72 and telephone set 72', the said circuit being completed from the sleeve 54 of plug 42 to the ring 52 of said plug through the switch 62 in its open position and the breaker point 56 of the key 44.

To ring the subscriber at the telephone set 72', the operator will then operate generator 46, thereby automatically closing switch 62 as explained above. It will be seen that only telephone set 72' will receive this ringing signal, inasmuch as the insertion of the plug 42 into the jack 10 has caused ring contact 24 to move upwardly, thereby disconnecting the ring contact 24 from the sleeve contact 26, and isolating the line 14 from the generator 46.

There has thus been disclosed an extremely simple method of connecting two telephone lines together and of ringing one of them. The operators sole steps, after he has connected the operator's set 18 to the calling line 14, consists of joining the two lines 14, 14' by means of the patch cord 20 and then turning the hand generator 46 in order to ring the called line.

In those rare cases where the operator desires to ring back the calling station, namely, telephone set 72, his sole step consists in turning the reversing key 44 whereby the ringing signal generated by the generator 46 will be impressed upon the line 14 through the breaker point 64 of the switch 62 and the breaker point 60 of the key 44.

After the two subscribers have been connected and have started their conversation, the operator may remove the plug 42, thereby disconnecting his set from the circuit. One or both of the annunciators 16, 16' may be left on the line a supervisory signal.

The foregoing description discloses what is at present a preferred embodiment of the invention, the invention being fully defined and pointed out in the appended claims:

What is claimed is:

1. A telephone switchboard system comprising means terminating a plurality of telephone lines, means whereby a signal impressed on one of said lines may be evidenced at the switchboard, an operator's set adapted to be connected to said line whereby communication may be had through a switchboard operator to the said line, means whereby a second line may be connected to the first named line through said operator's set, ringing means integral with said operator's set whereby a signal may be impressed on said second named line, said ringing means comprising a generator connected across said second named line through a normally-open switch, said generator including means whereby the said switch will close when the generator is operated, whereby operation of said generator will impress a ringing signal on said second named line, and the said operator's set further including ringback key means whereby the said generator may be placed across said first named line in order to ringback said first named line.

2. The system as described in claim 1, and means included therein whereby the ringing signal may be placed on a predetermined one of said lines.

BERNARD C. GROH.
